UNITED STATES PATENT OFFICE.

WILLIAM L. HOPKINS, OF ROSLYN, NEW YORK, ASSIGNOR TO AMERICAN LITHOGRAPHIC COMPANY, OF NEW YORK, N. Y., A CORPORATION OF NEW YORK.

DISPLAY DEVICE.

Application filed March 7, 1922. Serial No. 541,798.

To all whom it may concern:

Be it known that I, WILLIAM L. HOPKINS, a citizen of the United States, and a resident of Roslyn, in the county of Nassau and State 5 of New York, have invented certain new and useful Improvements in Display Devices, of which the following is a specification.

This invention relates to display devices 10 such as are adapted for use in connection with containers, particularly bottles, and has as an object to provide a unitary device having means integral therewith for attachment and support directly upon the 15 container.

Another object is to provide such devices in forms adapted for use as advertising mediums, to bear data relative to the contents of the containers and other analogous objects 20 to which they are attached. A further object is to provide display devices in designs inexpensive to construct and which are readily erected on a bottle or removed at will.

25 To these purposes my improvements comprise features hereinafter described in their preferred embodiment and illustrated in the accompanying drawing, in which:—

Figure 1 is a perspective front view of a 30 conventional type of bottle, showing the application of the preferred embodiment of my invention. Fig. 2 is a plan view showing the flat blank prior to bending. Fig. 3 is a similar but fragmentary view showing a 35 modification in construction. All of the figures are to one scale.

The shape of the display device is immaterial, so far as the outline of its upper portion or body is concerned, and also the material, except that it be flat, flexible and 40 amenable to ordinary die processes of cutting, creasing and bending. For purposes of illustration a bottle is shown in Fig. 1 consisting of a cylindrical body 6, its upper 45 part being curvilinearly contracted to form neck 7 terminating in a beaded rim 8 encircling the mouth, which is provided with a stopper 9. The blank, as indicated, comprises body or main portion 10 having any 50 preferred profile, its side edges 11 terminating at points equidistant from the upper edge 12 and being joined by converging curves 13 blending into a connecting curve 14 preferably ovoidal or semi-elliptic in 55 shape, these curved edges outlining a tab-

like element 15. In some cases there is provided bending crease 16, extending across tab 15, approximately at the junction of curves 13 and 14 and parallel with upper edge 12. An opening 17, preferably oval in 60 form, is provided through tab 15, its major diameter being on the vertical median line of the blank and its upper edge adjacent crease 16. A substantially U shaped incision 19, having out-turned ends 20, is made in 65 body 10 on said median line, forming lip 21, above oval opening 17, said lip when pressed outwardly presenting an opening 22. When erected on a bottle or the like, oval opening 17 is passed over bottle neck 7, 70 becoming seated on the lower portion thereof and the blank vertically flexed throughout its width so that stoppered mouth 8 and the upper part of neck 7 extend through opening 22, maintaining the device in op- 75 erative position.

Lip 21 is adapted to press against said neck materially augmenting the gripping function of the openings but permitting the device to be rotated on neck 7, and applied 80 or removed with ease. In the modification indicated in Fig. 3, the same general characteristics are maintained, except that in place of a continuous curved edge at the bottom of tab 15', the material is cut away 85 presenting opposed prongs 23 at the sides of oval opening 17', which is now partially open at the bottom, as shown. This arrangement, while holding the display device with equal security to the bottle, admits of more convenient assembling, particularly if the bottle necks are irregular or 90 vary in size.

From the foregoing it will be seen that a neat appearing and effective display device 95 has been devised, capable of extensive use and which, due to its simplicity, can be made at a moderate cost.

I claim:

1. In a display device of sheet material 100 adapted for erection on a bottle or the like, the combination of a body having a U shaped cut therethrough whereby an opening and a lip are provided, said opening being adapted for receiving the neck of the bottle there- 105 through and said lip adapted for pressing against said neck, and a second opening below said U shaped opening adapted for engag- 110 ing the lower portion of the bottle neck, said display being adapted to be flexed when

- erected on the bottle, whereby said openings are brought into engaging relation with the bottle.
2. In a display device of sheet material adapted for erection on a bottle or the like, the combination of a body having a U shaped cut therethrough whereby an opening and a lip are provided, said opening being adapted for receiving the neck of the bottle therethrough and said lip adapted for pressing against said neck, and a second opening of oval contour below said U shaped opening adapted for engaging the lower portion of the bottle neck, said display being adapted to be flexed when erected on the bottle whereby, said openings are brought into engaging relation with the bottle.
3. In a display device of sheet material adapted for erection on a bottle or the like, the combination of a body having a U shaped cut therethrough whereby an opening and a lip are provided, said opening being adapted for receiving the neck of the bottle therethrough and said lip adapted for pressing against said neck, a second opening below said U shaped opening adapted for
- engaging the lower portion of the bottle neck, and a transverse folding line between said openings, said display being adapted for bending along said folding line when erected on the bottle, whereby said openings are brought into engaging relation with the bottle.
4. In a display device of sheet material adapted for erection on a bottle or the like, the combination of a body having a U shaped cut therethrough whereby an opening and a lip are provided, said opening being adapted for receiving the neck of the bottle therethrough and said lip adapted for pressing against said neck, a second opening of oval contour below said U shaped opening adapted for engaging the lower portion of the bottle neck, and a transverse folding line between said openings, said display being adapted for bending along said folding line when erected on the bottle, whereby said opening and holding means are brought into engaging relation with the bottle.

In witness whereof, I hereby affix my signature this 4th day of March, 1922.

WILLIAM L. HOPKINS.
